WIRE-BOUND BOX LIDDING MACHINE

Leland H. Platt, John D. Platt, and Leland H. Platt, Jr., Los Angeles, Calif.

Application July 17, 1950, Serial No. 174,294

24 Claims. (Cl. 100—57)

1

This invention relates generally to machines for lidding or closing boxes and especially those of the type known to the trade as flexible walled "wire-bound" boxes. More particularly, the invention concerns improved lidding machines of the general type disclosed in our copending applications Serial No. 752,854, filed June 5, 1947, on Wire Bound Box Lidder, now Patent No. 2,517,710, issued August 8, 1950, and application Serial No. 19,908, filed April 9, 1948, on Produce Box Lidder, now Patent No. 2,550,292, issued April 24, 1951.

Wire-bound boxes, as are now widely used for many packing purposes, have certain distinctive structural characteristics which introduce a number of lidding problems not met in other types of boxes. For one thing, the flexible side and end walls of these boxes are susceptible to considerable outward bulging upon pressural application of the cover to the box, which bulging if permitted prevents proper interfitting of the cover with the box. Further, certain problems are presented by the manner in which the cover of a wire-bound box is fastened in closed condition, specifically by the interlocking of flexible cover carried and box carried projections, generally formed as interengageable wire loops.

The general object of the present invention is to provide a machine adapted to perform a complete cover closing and fastening operation on a wire-bound box of the above character with maximum operative efficiency, and preferably entirely automatically. As will appear, the machine acts upon a single actuation to brace the flexible box walls against bulging, close the cover, straighten and aline the box and cover carried wire loops to assure their interengagement, deform and interlock the wire loops and eject the closed box from the machine. Particularly contemplated is an automatic machine in which the various cover closing, loop straightening and loop interengaging operations are so interrelated as to complete the fastening of a box in a minimum of time.

A more specific object of the invention is to provide improved means for effectively and efficiently interlocking the cover fastening loops of a wire-bound box, and including improved mechanism both for properly alining the loops to interengage upon closing of the cover and for effectively crimping the loops together after their interengagement. With reference first to the alinement of the loops, we attain a high degree of accuracy in such alinement by the provision of apparatus adapted to engage and straighten the

2

loops after the cover has moved downwardly to a condition near its closed condition and preferably just prior to the actual interengagement of the loops. With the cover in this nearly closed condition, the alining mechanism is operable to simultaneously and in a single operation straighten both the box carried and cover carried loops. To assure proper interengagement of the loops they are positively retained in this accurately alined relation as the cover is brought down to its completely closed condition. Structurally, the alining mechanism may include one or more pairs of relatively movable jaws engageable upon closing with the opposite sides of both the cover carried and box carried loops to straighten them for interengagement as the cover is subsequently closed. To facilitate the interengaging reception of one loop within the other, the jaws may be specially designed so that one of the loops is closed to a narrower condition than the other.

We have found that the cover fastening loops of a wire bound box may be interlocked most rapidly and effectively by employing a number of individual crimping heads movable downwardly into engagement with the loops at the same time that the box is itself shifted horizontally. Further, this same shifting movement may be employed to displace the box away from the loop alining mechanism after an alining operation in preparation for its ultimate ejection from the machine. In this connection, certain rather specific features of the invention involve the manner of shifting the box into and out of its loop alining or interengaging position, preferably by movement of a pair of pressure elements which serve also to engage the opposite sides of the box and prevent their bulging as the cover is applied. A portion of the support on which the box is carried may itself be shifted with these plates. Further, we prefer to lower the central portion of the support during the final cover applying operation to accommodate a central bulge in the bottom of the box.

Additional features of the invention involve the preferred construction and relative positioning of the various crimping heads. Specifically, the heads may carry a pair of spaced rollers at opposite sides of their projection engaging portions for engaging and rolling along the box surface as the projections are crimped. Also, when a series of spaced heads are employed for engaging as many sets of interlockable loops, the center heads of the series may be elevated somewhat above the end heads to accommodate a central bulge in the cover as ultimately applied.

As mentioned above and as disclosed in our prior applications, we prevent bulging of the flexible box side and end walls during application of the cover by employing specially formed pressure members engageable with these sides to resist such bulging. To coact with these pressure members, the present invention contemplates improved means for closing the cover in a manner assuring a most effective overall box handling operation. Specifically, we may provide guide means engageable with the box cover as the box moves into the machine to deflect the cover downwardly to a partially closed condition. The projection crimping heads may themselves complete the closing of the box just prior to the crimping operation. As to the construction of the pressure members themselves, the invention contemplates an improved form of end pressure plate for engaging the transverse end walls of the box and especially characterized by a mounting for horizontal swinging movement between retracted condition and an active box engaging position. The box cover may be directed into proper interfitting relation with the box as it is closed by means of a pair of guides carried by these end pressure members.

The above and other features and objects of the present invention will be better understood from the following detailed description of the typical embodiment illustrated in the accompanying drawings, in which:

Fig. 1 is a front view of a preferred form of box lidding machine embodying the invention;

Fig. 2 is a horizontal section through the upper portion of the machine taken on line 2—2 of Fig. 1;

Fig. 3 is an enlarged rear view of the apparatus;

Fig. 4 is a transverse vertical section taken on line 4—4 of Fig. 3 and drawn to the scale of Fig. 1;

Fig. 5 is a fragmentary transverse vertical section taken on line 5—5 of Fig. 3 and showing especially the clutch mechanism for controlling the operation of the machine;

Fig. 6 is a fragmentary vertical section taken on line 6—6 of Fig. 3 showing a portion of the mechanism for actuating the loop crimping heads or hammers;

Fig. 7 is a vertical section taken on line 7—7 of Fig. 3;

Fig. 8 is a fragmentary vertical section taken on line 8—8 of Fig. 3 and showing the mechanism for actuating the loop alining jaws.

Fig. 9 is a fragmentary vertical section taken on line 9—9 of Fig. 3;

Fig. 10 is an enlarged fragmentary perspective view of one of the pairs of loop straightening jaws;

Fig. 11 is a fragmentary horizontal section through the loop straightening apparatus taken on line 11—11 of Fig. 10;

Figs. 12, 13 and 14 are fragmentary perspective views showing a pair of box and cover loops at various stages during the straightening and interlocking operations;

Fig. 15 is a fragmentary plan view showing the manner in which the box sides are retained against bulging by the various pressure plates while the cover is being closed and the loops interlocked;

Figs. 16, 17, 18 and 19 show four different positions of one of the loop interlocking hammers at various stages during its operation.

Fig. 20 is an enlarged fragmentary perspective

view of a wedge member for retracting the stop by which the initial position of a box within the machine is determined;

Fig. 21 is a fragmentary horizontal section taken on line 21—21 of Fig. 4;

Fig. 22 is a fragmentary front view showing the manner in which a box lid is guided into its correct position with relation to the box walls.

Fig. 23 is a fragmentary perspective view of a variational form of box cover closing guide; and

Fig. 24 is a fragmentary perspective view of a box cover alining plate carried by the loop alining mechanism.

Referring first to Figs. 1 and 2, the illustrated box lidding apparatus includes a forward box supporting structure 10 comprising a number of rollers 11 onto which the wire-bound boxes 12 are successively fed from the right, as seen in these views, and from which the fastened boxes are delivered to the left. Conventional roller conveyors 13 and 14 at the opposite ends of the apparatus may serve to carry the box to and from the machine. As a box moves onto the supporting structure 10, its cover 15 is engaged and partially closed by the overlying guide rod 16. The box is stopped at a predetermined operative position on the supporting apparatus by a stop 15 projecting upwardly in the path of the box and adapted for automatic retraction downwardly during the subsequent operation of the machine. Upon arrival at the desired position on the box supporting structure, the box is tightly clamped at its opposite sides by outer and inner pressure members 16 and 17, and at its opposite ends by pressure members 18 and 19. The box and lid carried wire loops are then alined by actuation of the wire straightening apparatus generally indicated at 20, after which the crimping heads or hammers 21 are moved downwardly to completely close the lid edge against the box. At this point, the inner pressure member 17 is actuated outwardly to shift the box away from the straightening mechanism, and during that shifting movement the heads 21 engage and interlock the wire loops. The inner and end pressure members are then released and the box is ejected onto roller conveyor 14 in fastened condition.

The working parts of the machine may be carried by any suitable frame structure, here shown typically to comprise a base 24, a pair of vertically extending end columns 25, a pair of angular rear braces 26 extending between the base and the two columns 25 respectively, and a forward table structure 10 over which the boxes move (see Fig. 4). The major portion of the machine may be covered by a suitable sheet metal skin or housing 28, as shown.

At the opposite ends of box supporting structure 10, we provide a pair of powered rollers 29 which are continuously driven by a motor M and serve to advance the boxes onto and off of the central box supporting structure. These rollers are carried by a pair of spaced elongated shafts 30 rotatably mounted by bearings 31 and 32 and interconnected for rotation together by chain 34 near the rear of the machine. The drive from motor M is transmitted through a belt 36 engaging a pulley 35 carried by one of the shafts.

The power for effecting all of the operations of the machine except the box movement to and from the machine is transmitted from motor M through a speed reducing unit 23 and a main cam shaft 22. For this purpose, the input shaft 37 of the speed reducing unit carries a pulley 38 driven by the motor through belt 39.

This wheel 38 is at times free running on shaft 37 but is adapted to be rotatively interlocked with the shaft by axial movement of a conventionally illustrated clutch element 40 (see Fig. 5). When clutch element 40 is engaged with wheel 38, the output shaft 41 of the speed reducing unit is power driven, and in turn drives the main cam shaft 22 through chain and sprocket drive 42 (see Figs. 3 and 4). The cam shaft is rotatively mounted to the end columns 25 of the frame by a pair of bearings 43, and carries a number of cams C1, C2, C3, C4 and C5 which serve to actuate the various working parts of the machine in proper sequence.

Operation of clutch element 40 is controlled by a foot pedal 44 whose depression by an operator engages the clutch to energize the cam shaft for one complete revolution. Specifically, pedal 44 is connected by a rearwardly extending arm 45 to a clutch actuating shaft 46 mounted in bearings 47 at the rear of the machine. Shaft 46 carries an upstanding arm or lug 48 which is pivotally connected at its upper end to a forwardly extending link 49. This link pivotally connects with a horizontal lever 50 mounted at one end 51 to the frame and pivotally connected at its opposite end 51 to a vertically extending swinging frame structure 52. This clutch actuating frame may comprise a pair of parallel arms 53 interconnected and mounted for pivotal movement at their upper ends 54 and rotatively carrying clutch element 40 between their lower ends by an annular yoke 55. As will be understood, depression of pedal 44 and consequent rotation of shaft 46 swings arm 48 forwardly and through link 49 and lever 50 swings frame 52 forwardly to engage the clutch and start the rotation of the cam shaft. The swinging frame 52 is normally urged rearwardly in a clutch disengaging direction by spring 56 connected at one end to lever 50 and at the opposite end to post 57 extending upwardly from the base of the machine.

A rotatable roller 58 is carried between arms 53 of the swinging clutch actuating frame 52 at a location between its point of connection 51 with actuating lever 50 and its upper mounting end 54. Cam C1, carried by the cam shaft 22 opposite this roller, has a circular outer surface containing a recess 59 within which roller 58 is received when the clutch is disengaged. When the foot pedal is depressed to engage the clutch, cam shaft 22 commences to rotate and turn cam C1 to a position in which roller 58 is no longer opposite recess 59. The outer circular surface of cam C1 then retains roller 58 and frame 52 in their actuated clutch engaging positions until the completion of one revolution of the cam shaft. When the cam shaft has made one complete revolution, recess 59 returns to its initial position opposite roller 58 to permit disengagement of the clutch under the influence of spring 56 and to thus stop the operation of the machine until the pedal is again depressed.

To prevent the admission of boxes to the machine while it is operating and to prevent the operation of the machine while a box is entering or leaving, we provide a pair of elongated box entrance and exit feelers 60 and 61 pivotally mounted at 62' to the frame of the machine and normally projecting into the box path. A pair of elongated rods 64 and 65 form together a connection between the two feelers 60 and 61 interconnecting them for swinging movement together between their forwardly projecting Fig. 2 positions and retracted positions at the side of

10
15
20
25
30
35
40
45
50

the box path. Specifically, rods 64 and 65 are pivotally connected at their outer ends 66 and 67 to the angular inner portions 63 of the two feelers, and are pivotally connected together and to a horizontal control disk 68 at their inner ends 69. Disk 68 is mounted to the frame at 73 for rotation about a vertical axis. The foot pedal operated shaft 46 rigidly carries an upstanding arm 70 (see Figs. 2 and 5) having a roller 71 at its upper end receivable within recess or notch 72 in disk 68 during operation of the machine. When pedal 44 is actuated to engage the clutch and set the machine in operation, arm 70 is swung forwardly by rotation of shaft 46. The resulting movement of roller 71 into 72 prevents rotation of disk 68 and thus locks feelers 60 and 61 in their outwardly projecting positions to prevent the admission of a second box to the machine while a first box is being fastened. When the cycle of operations on one box is completed, arm 70 swings rearwardly to release the disk 68 for rotation and thus permit the closed box to leave past feeler 61 and the next successive box to enter past feeler 60. Spring 74, resisting retraction of the feelers, may be sufficiently strong to prevent the deflection of feeler 60 by an entering box alone while yielding to the force exerted by both an entering and a leaving box, so that the admission of boxes is controlled entirely automatically. While a box is entering or leaving the machine, feelers 60 and 61 are deflected by that box to a position rotating disk 68 from its Fig. 2 position to thus prevent actuation of the clutch engaging mechanism. In this manner, we prevent damage to both the machine and box such as might result from accidental operation of the machine with the box improperly positioned.

As a box 12 is moved into position from the right as seen in Fig. 1, its cover 75 is deflected 40 downwardly by the elongated guide rod 76 to a condition in which the loop straightening and interlocking mechanisms are able to function. This rod extends in the direction of box travel and includes an inclined entrance end 76a by which 45 the box cover is wedged downwardly as it enters the machine and a main horizontal portion 76b extending over the box supporting structure 10. The cover closing rod may be carried by a pair of vertical arms 77 connected to a pair of brackets 78 projecting outwardly from the frame above the box.

Box stop 15 (Figs. 1 and 2) is the upwardly extending end portion of an elongated lever arm 79 which extends in the direction of the box 55 travel beneath the box supporting rollers. This lever is mounted at 80 for pivotal movement between a condition in which stop 15 projects upwardly into the box path and the Fig. 1 condition in which the stop is retracted downwardly. 60 At the entrance end of the machine, lever 79 has an upstanding portion carrying an inclined plate 81 engageable by an entering box to pivot the lever in a direction raising stop 15. Thus, each box upon entering the apparatus automatically 65 actuates the stop to a position limiting the box movement at the desired fastening position. The mounting at 80 is of a type offering frictional resistance to any unintended actuation of lever 79, and thus retains the stop in elevated position until its later mechanical retraction.

The box supporting structure 10 comprises a series of transverse rollers 11 rotatably carried at their outer ends by a rod 82 and at their inner ends by an elongated member 83. Rod 82 and member 83 are rigidly interconnected by a pair

75

of transverse frame elements 84. Rod 82 is pivotally secured at its opposite ends to the lower portions of a pair of vertically extending bars 85 carrying near their upper ends the outer pressure plate 16 for engaging and resisting bulging of the outer side of the box. This outer pressure plate extends above the outer box wall to a position opposite the outer edge of the cover and serves to engage the cover and retain its outer edge in correct relation to the box. Bars 85 are secured to the outer ends of a pair of transverse rods 86 which are suitably mounted to the frame of the machine for axial movement only. Thus, the entire roller supporting assembly 10 and the associated outer pressure plate 16 may be moved transversely of the box path as permitted by such axial movement of rods 86. Each of these rods carries a collar 87 against which a spring 88 acts to normally urge the supporting assembly and outer pressure plate to their outer positions of Fig. 2.

As the machine operates, cam C3 acts to displace this transversely movable assembly inwardly to position a carried box for the loop straightening and interlocking operations. For this purpose, we provide a lever 89 (see Figs. 3 and 7) pivotally mounted at its lower end 90 to the base of the machine and carrying near its upper end a roller 91 engageable with the outer surface of cam C3 to follow its movement. The upper end of lever 89 is connected by a forwardly extending rod or link 92 to the upper end of a link 93 pivoted to the frame at 94. The pivotally interconnected ends of links 92 and 93 are pivotally connected to a lug 95 depending from the rear roller mounting member 83 of the movable box supporting structure. Cam C3 is shaped as shown in Fig. 7, and is normally in the position of that figure, in which the box supporting structure and outer pressure plate are in their outer positions. Upon rotation of cam shaft 22, cam C3 swings arm 89 rearwardly to displace the box supporting structure and a carried box rearwardly into fastening position. By virtue of the pivotal mounting of link 93 at 94, the box supporting structure, including rollers 14, swings somewhat downwardly at the inner end of its travel to release the box for support by only the powered rollers 29. Thus, the underside of the box is permitted to bulge slightly in a manner facilitating the accommodation of the produce within the box.

The two end pressure plates 18 and 19 are mechanically connected to the box supporting structure and outer pressure plate 16 to be automatically actuated into their box clamping positions as the box is shifted inwardly in the above described manner. For this purpose, the end pressure plates 18 and 19 are carried by a pair of upwardly and outwardly extending arms 96 rigidly carried at the upper ends of shafts 97 which are suitably mounted, as by bearings 98 and 99, for rotation about vertical axes at the opposite ends of the machine. The lower end of each of these shafts 97 carries an arm 100 pivotally connecting with a link 101 which in turn pivotally connects with the inner end 102 of the corresponding shaft 86. Thus, as the box supporting structure and shafts 86 move inwardly under the influence of cam C3, the movement is transmitted through links 101 to pressure plates 18 and 19 to close them against the ends of the box.

Each of the end pressure plates 18 and 19 has associated with it an upstanding cover guiding plate 103 having an angular upper portion 104 by

which the box cover is directed into proper relation with the box as it is closed. These cover directing plates are attached directly to arms 96, as by screws 105, and carry the associated pressure plates 18 and 19 by screws 105a. Since the end walls of the box are inwardly offset from the corresponding edges of the cover, each of the pressure plates 18 and 19 is spaced from the associated cover directing plate by suitable spacer sleeves 106.

The box stop 15 is adapted to be automatically retracted from the box path in response to the above inward shifting movement of the box. To effect such retraction of the stop, we provide on the under side of one of the transverse members 84 of the box supporting structure a wedge element 107 (see Figs. 2 and 20) engageable with an upstanding tab 108 on lever 79 to shift that lever upon inward movement of the box supporting structure.

With the four sides of the box tightly clamped against bulging by their respective pressure members 16, 17, 18 and 19, the wire loop straightening mechanism 20 and the crimping heads 21 proceed to straighten and align the various box and cover loops 109 and 110 and to interlock them to the condition of Fig. 14. The loop aligning mechanism includes a number of pairs of jaws 111 and 112 operable by movement together to accurately align the box and cover carried loops to the condition of Fig. 13 and retain them in aligned condition as the cover is subsequently brought down to its completely closed position. A first jaw 111 of each pair is attached to an upper horizontally elongated and horizontally movable bar 113 by a pair of screws 114. The other jaw 112 of each pair is attached by screws 115 to a second relatively movable horizontal bar 116 which projects outwardly beyond the bar 113. As will be understood, relative longitudinal movement of the two bars 113 and 116 moves the jaws 111 and 112 of each pair in a closing direction to effectively straighten the corresponding loops. For engaging and straightening the horizontally projecting lid carried loops 110, the jaws have a pair of parallel vertical upper wall portions 117 and 117' projecting perpendicularly outwardly from the upper sliding bar 113. At the outside of bar 116, the jaws have a pair of angular opposed surfaces 118 positioned relatively closer together than walls 117, 117' and adapted to engage and straighten the relatively narrower box carried loops 109.

The two bars 113 and 116 are slidable horizontally along the forward face of a mounting plate 119 which extends between the side columns 25 of the machine frame. These bars are retained to plate 119 for such sliding movement by connection to a pair of vertically spaced sliding bars 120 and 121 at the rear of the plate. As seen in Fig. 11, bar 113 is rigidly connected to bar 120 by a number of screws 122 extending through elongated guiding slots 123 in plate 119. Bars 116 and 121 are similarly interconnected and guided.

The loop straightening jaws are actuated in accordance with the rotation of cam C4 through a lever 124 pivotally connected at 127 to the lower end of a vertically extending rod 128. The upper end of this rod is pivotally connected at 129 to an arm 130 projecting from pinion 131 which engages a pair of racks 132 and 133 carried by bars 120 and 121. Rod 128 carries a collar 134 intermediate its ends against which spring 135 bears to normally urge the rod upwardly and

as a result to urge roller 126 against cam C4. As will be understood, rotation of cam C4 effects downward movement of lever 124 and rod 128 which in turn rotates pinion 131 and displaces racks 132 and 133 in opposite directions. Such rack movement is transmitted to the jaws 111 and 112 which are thus moved together to straighten and aline the box and cover carried loops from their initial condition, as represented by Fig. 12, to the condition of Fig. 13.

The flexible end walls 212 of a conventional wire-bound box are reinforced at their side and bottom edges by outwardly projecting relatively rigid cleats 214, two of which serve as upstanding corner posts 214a of the box at opposite ends of its loop carrying wall (see Fig. 15). While these corner posts are ordinarily retained in their proper upright conditions by their own rigidity and by engagement of end plates 18 and 19 with the main flexible portions of the end walls, we have sometimes found it necessary to independently position and retain the corner posts during the cover closing operation in order to assure accurate interfitting of the cover and box and of their wire loops. For this purpose, we prefer to provide means carried by the loop straightening mechanism and operable upon its actuation to engage and position the corner posts. Specifically, upper bar 113 of the loop straightening mechanism carries at one end a forwardly projecting vertical plate 213 (see Fig. 10) adapted to engage a corresponding one of the corner posts and displace it upon jaw closing actuation of the straightener. The upper portion of this plate is disposed angularly to form a guide for engaging and guiding the cover as it is closed. Similarly, the lower bar 116 of the loop straightener carries at the opposite end of the machine a plate 215 (see Fig. 24) serving to straighten the opposite corner post of the box and having an angular portion 216 for guiding the corresponding end of the cover.

Each of the crimping heads 21 has a vertically extending stem portion 136 and a lower transverse portion 136a carrying a pair of rollers 137 at its opposite ends. After the box has been shifted inwardly to its fastening position, these heads 21 are actuated downwardly from the position of Fig. 16 to the position of Fig. 17 to displace the box cover 75 downwardly between the positions of those two figures. Each of the cover carried loops 110 is by this downward movement located between the upper wall portions 117 of one of the pairs of loop straightening jaws. With the crimping heads in the position of Fig. 17, the straightening jaws are actuated in the manner previously described to straighten and aline the various sets of loops. While the jaws are held in their closed alining conditions, the heads 21 are further lowered to the position of Fig. 18 to close the lid and move the cover carried loops downwardly about the box carried loops. At this point, the box is shifted outwardly away from the straightening mechanism so that the upwardly projecting loops 109 are engaged by the heads and bent away from the box in an interlocking direction. Finally, heads 21 are further lowered at the side of the box to the condition of Fig. 19 to complete the interlocking of the loops. As seen best in Fig. 1, the central crimping heads are elevated slightly above the end heads to accommodate a central bulge in the lid.

The crimping heads are driven in the above manner by cam C2 whose operation is best seen

in Figs. 3 and 6. The movement of this cam is followed by a lever 138 pivotally mounted at 139 to shaft 125 and extending forwardly to pivotally connect at 140 with the lower end of a vertically extending rod 141. Lever 138 carries a roller 142 engaging the cam C2 to follow its movement. The upper end of rod 141 carries a collar 143 rotatably received about an upper horizontal shaft 144 which extends parallel to the path of the box through the machine. The opposite ends of shaft 144 are connected to a pair of vertically swinging parallel arms 145, each of which is mounted at its rear end 146 on a bracket 147 projecting rearwardly from one of the columns 25 and extends forwardly to a location in front of that column. The arms 145 are thus free for vertical swinging movement of lever 138 and rod 141 as effected by cam C2. A bar 148 of square section extends between the swinging arms 145 at a location forwardly of shaft 144 and is mounted for rotation relative to these arms. The crimping heads are attached to this square section rod by individual mounting brackets 149 having tubular portions 150 received about the bar and having vertically extending openings 250 (see Fig. 16) within which stems 136 of the hammers are adjustably received. The heads may thus be adjusted both horizontally and vertically to accommodate boxes of different sizes.

During their final downward movement, the crimping heads are swung outwardly in the direction of box movement as well as downwardly to follow the shifting movement of the box in a manner assuring complete interlocking of the loops. This outward swinging movement is attained by mounting about one end of shaft 144 a sleeve 244 carrying a downwardly extending lever arm 151 and an upwardly extending lever arm 152 whose positions determine the angularity of the crimping heads. The depending arm 151 carries at its lower end a roller 153 received within and guided along a cam slot 154 formed in a plate 155 which extends across the inner side of the adjacent column 25. This cam slot extends vertically along most of its extent but curves forwardly at its lower end 255. Upwardly extending lever arm 152 is pivotally connected by link 157 to an arm 156 carrying a lower horizontal tubular portion of square cross section received about shaft 148 and controlling its angular position. As shaft 144 and swinging arm 145 are moved downwardly by cam C2 to actuate the crimping heads, roller 153 first follows the vertical portion of slot 154 to maintain the heads in substantially vertical positions. However, as the heads near the lower end of their travel, roller 153 follows the curved portion of slot 154 to swing the heads forwardly to the position of Fig. 19.

The inner pressure member 17 comprises an elongated horizontally extending channel 158 which may carry along its upper surface an angle iron 159 forming with the channel a forward box engaging surface of considerable extent. The channel is mounted for movement transversely of the box path by attachment to a pair of rearwardly extending rods 160 each guided for axial movement by passage through a pair of spaced ears 161 of a U-shaped mounting bracket 162 carried by the machine frame. Each of the rods 160 carries a collar 163 against which a spring 164 bears to normally urge the pressure member 17 rearwardly to its Fig. 2 position. Member 17 is adapted for powered movement

11

outwardly under the influence of cam C5 to shift the box from its inner loop alining and inter-engaging position. The shifting force is transmitted from the cam to member 17 by a lever assembly 165 (see Figs. 3 and 9) which comprises a horizontal shaft portion 166 pivotally mounted to the frame and carrying a depending arm 167 whose roller 168 follows the cam movement and an upwardly extending arm 169 connected by link 170 to the pressure member.

To supplement the action of powered rollers 29 in ejecting a box after a fastening operation, we provide an auxiliary ejecting device 171 adapted to be conditioned for operation by the shifting movement of the outer pressure plate assembly relative to the frame of the machine. This device includes a lever 172 pivotally connected at 173 to the one of the upstanding members 85 nearest the entrance end of the machine. This lever carries at its lower end an inwardly projecting element 174 adapted to engage the rear wall of the box and to eject the box from the machine upon clock-wise pivotal movement of the lever as seen in Fig. 1. The upper end of lever 172 is connected by a universal connection 175 to the upper end of an actuating rod 176 which extends downwardly through an opening in a bracket 177 carried by the stationary frame. Beneath bracket 177, rod 176 has an enlargement 178 which will not pass through the opening in the bracket. Consequently, as member 85 is shifted inwardly to move the box to fastening position, enlargement 178 engages the underside of bracket 177 to limit the upward movement of the rod and as a result to effect counter clock-wise rotation of lever 172. This rotation of the lever swings element 174 rearwardly to a position of engagement with the rear wall of the box. When member 85 is subsequently shifted outwardly, reverse pivotal movement of the lever 172 is prevented by engagement of element 174 with the rear of the box, which is itself retained against ejecting movement by engagement with feeler 61. Consequently, rod 176 moves downwardly relative to bracket 177 and against the tendency of spring 179 in a manner storing ejecting energy in the spring. Upon release of the box for ejection, spring 179 displaces rod 176 upwardly to rotate lever 172 in a direction commencing the ejecting movement of the box.

In operation, boxes are successively fed to the machine from conveyor 13 and are delivered in fastened condition to conveyor 14 along which they may pass to a loading platform, warehouse or any suitable distribution or storage location. Movement of the boxes onto and off of supporting structure 10 is effected primarily by rollers 29 which as previously brought out rotate constantly. As a box enters the machine, its cover 75 engages overhead rod 76 by which it is pressed downwardly to a condition in which the loop straightening and fastening mechanisms are able to function. Also, as the box enters, it engages and depresses plate 81 to pivot lever 79 and elevate stop 15 into the box path. Upon arrival at a predetermined position on supporting structure 10, the box engages stop 15 and is retained against further advancing movement, at which point the operator presses foot pedal 44 to engage the clutch 39, 55 through linkage 48, 49, 50 and 52 and commence a cycle of operation. Engagement of the clutch energizes the speed reducing unit 23 to rotate the main cam shaft 22 through one complete revolution after which

12

the reception of roller 58 within notch 59 of cam C1 permits automatic disengagement of the clutch. Clutch engaging rotation of shaft 46 swings arm 70 forwardly to move its upper roller 11 into notch 72 of disk 68 to prevent the admission of a box to the machine while it is operating.

As the cam shaft 22 rotates through one complete revolution, the various cams C2, C3, C4 and C5 actuate their associated mechanisms in proper sequence to effect a complete lidding operation. First, cam C3 swings its following lever 89 rearwardly to shift the box supporting structure 10 and the outer pressure plate 16 rearwardly and thus clamp the box between plate 16 and member 17 to effectively retain its opposite sides against bulging. This inward movement of the box causes the box carried loop 109 to engage bar 116 of the alining mechanism and be straightened to an upstanding condition. At the same time, the end pressure plates 18 and 19 are swung inwardly by reason of their connection through links 101 with rods 86 of the box supporting structure to brace the transverse central portions 25 of the box ends near their upper edges against bulging. Such movement of the end pressure plates 18 and 19 into active position also moves the associated guides 103 into position for directing the box cover downwardly in proper relation to the box.

When the top edge portions of all four sides of the box are thus retained against bulging, a first increased diameter portion 180 of cam C2 moves into engagement with its following roller 40 to swing lever 138, rod 149 and upper levers 145 downwardly in a manner actuating crimping heads 21 to their Fig. 17 positions in which the loop alining apparatus is able to function. While the portion 180 of cam C2 retains the crimping heads in the Fig. 17 position, cam C4 comes into play to actuate lever 124, rod 128 and arm 130 downwardly to rotate pinion 131 and by such rotation displace racks 132 and 133 in opposite directions. This rack movement effects corresponding relative longitudinal sliding movement between the two bars 113 and 116 to move the various pairs of straightening jaws 111 and 112 in closing directions. As the jaws close, their upper wall portions 117 engage and straighten the cover carried loops 110, and the inwardly offset angular surfaces 18 engage and straighten the box carried loops 109.

While cam C4 retains the alining jaws in their closed condition to retain proper alinement of the loops, a second cam surface 181 of cam C2 engages roller 142 to further lower the crimping heads to the condition of Fig. 18 to completely close the cover 75. After such closing movement of the cover has interengaged the box and cover carried loops, cam C4 releases its lever 124 to permit separating movement of the various set of loop straightening jaws under the influence of spring 135. At this point, cam C5 actuates lever assembly 165 to move the inner pressure member 17 outwardly in a manner shifting the box away from the wire straightening mechanism. Cam C3 is formed to move the outer pressure plate 16 outwardly in correspondence with this shifting movement of the inner pressure member to assure retention of the opposite box sides against bulging until the loops are completely interlocked. As the box is shifted outwardly by the inner pressure member, a final increased diameter portion 182 of cam C2 comes into play to further lower the crimping heads be-

tween the positions of Fig. 18 and Fig. 19. This final lowering movement of the heads bends the box carried loops downwardly about the cover carried loops to tightly interlock them and fasten the cover in closed condition. As previously brought out, the crimping heads swing outwardly during their final lowering movement to follow the outward shifting of the box and thus assure complete interlocking of the loops.

After the box has been shifted to its outer position, pressure member 17 returns inwardly and as the cam shaft completes its single revolution the clutch is automatically disengaged to leave only the rollers 29 operating. Removal of roller 71 from notch 72 in disk 78 by the automatic disengagement of the clutch releases the disk for rotation to thus permit swinging movement of feelers 60 and 61 in a direction passing the fastened box onto the discharge conveyor 14 and admitting the next successive box into the machine from entrance conveyor 13. The ejection of the first box from the machine is initiated by ejecting device 171, which as previously described is conditioned by the inward shifting movement of the outer pressure plate.

Fig. 23 shows a variational form of cover closing guide 276, corresponding essentially to the guide 76 described above but having the advantage of offering no frictional resistance to the movement of boxes through the machine. Guide 276 includes a body plate 277 suitably attached to the machine frame and about which an endless chain 278 is movably mounted by sprockets 279 carried by the plate. The lower cover engaging portion of the chain has an angular entrance portion 280 and a horizontal main portion 281 serving the functions of displacing the box cover downwardly as the box enters the machine and retaining it down during the loop straightening and interlocking operations. The chain may be driven by motor M through any suitable drive connection including typically a drive chain 282. The speed at which guide chain 278 is driven should of course correspond to the rate at which a box is advanced into the machine by the entrance of one of the two powered rollers 29.

We claim:

1. A wire-bound box lidding machine comprising a support onto which is movable a box having an upwardly opened hinged cover and having a flexible vertical wall, the cover and box edges carrying interlockable wire loops, guide means engageable by the cover during movement of the box onto the support and positioned to displace the cover downwardly toward the box and retain it in a lowered but partly open position, a movable member engageable with said flexible wall to resist bulging thereof while the cover is retained by said guide means, means for actuating said member to engage the box wall after movement of the box onto the support and following said downward displacement of the cover but while the cover remains partly open, and means for thereafter interlocking said loops and fully closing the cover while said member engages and resists bulging of said flexible wall.

2. A wire-bound box lidding machine comprising a support onto which is movable a box having an upwardly opened hinged cover and having a flexible vertically extending wall, the cover and box edges carrying interlockable wire loops, guide means engageable by the cover as the box moves onto the support and positioned to displace the cover as a result of such movement downwardly

toward the box and retain it in a lowered but partly open position, a member extending transversely of the path of movement of the box onto the support and engageable with said flexible wall to resist bulging thereof while the cover is retained by said guide means, means mounting said member for movement relative to the support into and out of said path and engagement with the box wall, means for actuating said member to engage the box wall after movement of the box onto the support and following said downward displacement of the cover but while the cover remains partly open, and means for thereafter interlocking said loops and fully closing the cover while said member engages and resists bulging of said flexible wall.

3. A wire-bound box lidding machine comprising a support onto which is movable a box having an upwardly opened hinged cover and having four flexible vertical walls, the cover and box edges carrying interlockable wire loops, guide means engageable by the cover during movement of the box onto the support and positioned to displace the cover downwardly toward the box and retain it in a lowered but partly open position, relatively movable members engageable with said flexible walls to resist bulging thereof while the cover is retained by said guide means, means for producing relative movement of said members to engage the box walls after movement of the box onto the support and following said downward displacement of the cover but while the cover remains partly open, and means for thereafter interlocking said loops and fully closing the cover while said member engages and resists bulging of said flexible wall.

4. A box lidding machine comprising a stationary frame, means carried by the frame for supporting a box having a cover carrying a flexible projection at one edge adapted to be interlocked with a second projection on an adjacent edge of the box, means for shifting the box relative to the frame, mechanism operable to engage and interlock said projections during the shifting movement of the box, and means for operating said projection interlocking mechanism in timed relation with said box shifting means.

5. A box lidding machine comprising a stationary frame, means carried by the frame for supporting a box having a cover carrying a flexible projection at one edge adapted to be interlocked with a second projection on an adjacent edge of the box, means for shifting the box relative to the frame and transversely of said edges, and a crimping head positioned in the path of one of said projections for engagement thereby during said shifting movement of the box to bend the projection in an interlocking direction.

6. A box lidding machine comprising a frame, means carried by the frame for holding a box having a cover carrying a flexible projection at one edge adapted to be interlocked with a second flexible projection on an adjacent edge of the box, one of said projections extending upwardly, a crimping head overlying the cover near said edge and movable downwardly thereagainst to close the cover against the box and interengage said projections, and means operable in timed relation with the cover closing movement of said head to horizontally shift the box while the crimping head is against the closed cover, said head when against the cover being positioned in the path of said one projection to be engaged thereby during the shifting movement

of the box and bend the projection in an interlocking direction.

7. A box lidding machine comprising a stationary frame, means carried by the frame for holding a box having an upwardly opened cover carrying an outwardly extending wire loop at one edge adapted to be interlocked with a second wire loop projecting upwardly from an adjacent edge of the box, a vertically movable crimping head overlying said edge of the cover, means for moving said head downwardly against the cover to close it against the box and interengage said loops, means for horizontally shifting the box transversely of and away from said edges while the crimping head is against the closed cover, said head when against the cover being positioned in the path of said upwardly projecting box carried loop to be engaged thereby during the shifting movement of the box and bend it about the cover carried loop and outwardly away from the box, and means then operable to move said head downwardly at the side of the box to bend the box carried loop downwardly thereagainst.

8. A box lidding machine comprising a stationary frame, means carried by the frame for supporting a box having a cover carrying a flexible projection at one edge adapted to be interlocked with a second projection on an adjacent edge of the box, means for shifting the box relative to the frame, a movable crimping member, and means operating in timed relation with said shifting means to move said member downwardly at the side of the box during said shifting movement to deform and interlock said projections.

9. A box lidding machine comprising a stationary frame, means carried by the frame for holding a box having an upwardly opened cover carrying an outwardly extending wire loop at one edge adapted to be interlocked with a second wire loop projecting upwardly from an adjacent edge of the box, a movable crimping head overlying said edge of the cover, means for horizontally shifting the box transversely of and away from the location of said edges, means for moving said crimping head first downwardly and then simultaneously downwardly and in the horizontal direction of box movement, and means for actuating said head moving means and said box shifting means in timed relation to first move the head downwardly to close the box cover and interengage said loops, then shift the box so that the head is engaged by said upwardly extending box carried loop to bend the loop outwardly, and then move the head simultaneously downwardly and horizontally as the shifting movement of the box continues to bend said box carried loop downwardly against the side of the box.

10. A box lidding machine comprising a support onto which may be moved a box having an upwardly opened cover carrying at one edge a flexible projection interlockable with a second projection on an adjacent box edge, said projections being interengageable by the final closing movement of said cover, means for moving the cover relative to the box between a nearly closed condition in which said projections are proximately positioned but not interengaged and closed condition to interengage the projections, a straightening means positioned near the location of said box edge and forming a guideway to receive and engage a side of the cover-carried projection while the cover is in said first nearly

closed condition to aline the cover carried projection for interengagement with the box carried projection, and a support carrying said member at the side of the box adjacent the projection-carried edge of the cover.

11. A box lidding machine comprising a support onto which may be moved a box having an upwardly opened cover carrying a flexible projection at one edge interlockable with a second projection on an adjacent edge of the box, means for displacing said cover relative to the box in a closing direction, projection alining means including spaced guides engageable with the sides of the cover carried projection after relative closing movement of the box and cover by said last mentioned means to aline the projection for interengagement with the box carried projection, and a movable support carrying said member at the side of the box adjacent the projection-carrying edge of the cover.

12. A box lidding machine comprising a support for holding a box having an upwardly opened cover carrying at one edge a flexible loop projection interlockable with a second loop projection carried by an adjacent edge of the box, means for displacing said cover relative to the box to a position near its closed condition, and upper and lower projection alining members positioned one above the other in direct proximity to said box edge and operable while the cover is in said downwardly displaced condition to engage and aline both the box and cover carried projections for interengagement, said members being engageable respectively with the cover-carried and box-carried projections and being relatively positioned to laterally deflect and aline the projections.

13. A box lidding machine comprising a support onto which may be moved a box having an upwardly opened cover carrying at one edge a flexible loop projection interlockable with a second loop projection on an adjacent box edge, said projections being interengageable by the final closing movement of said cover, means for moving the cover and box relatively between a nearly closed cover condition in which said projections are proximately positioned but not interengaged and closed condition to interengage the projections, upper and lower guides engageable respectively with the cover-carried and box-carried projections as the cover is closed toward the box and being relatively positioned to deflect the projections laterally into alinement as they are interengaged, and a common support for the guides at the side of the box.

14. A box lidding machine comprising a support onto which may be moved a box having an upwardly opened cover carrying at one edge a flexible loop projection interlockable with a second projection on an adjacent box edge, said projections being interengageable by the final closing movement of said cover, means for moving the cover downwardly toward its closed condition, and a pair of spaced elements forming a guideway engageable with a side of the cover carried loop as it is closed by said last mentioned means to position said cover loop for proper interengagement with the box loop.

15. A box lidding machine comprising a support for holding a box having a cover carrying at one edge a flexible projection interlockable with a projection on an adjacent box edge, alining mechanism adjacent which said box and cover edges are received and operable to engage and aline the projections for interengagement, mech-

anism operable to shift the box transversely of said edges and away from said alining mechanism, and means for actuating said box shifting means to move the box away from said alining mechanism after the alining operation.

16. A box lidding machine comprising a support for holding a box having a cover carrying at one edge a wire loop interlockable with a second loop on an adjacent box edge to fasten the cover closed, means for alining said box and cover carried loops for movement into interengaging relation, means for deforming and interlocking said loops, and mechanism operating to sequentially actuate said loop alining and interlocking means in predetermined timed relation.

17. A box lidding machine comprising a support for holding a box having a cover carrying at one edge a flexible projection interlockable with a projection on an adjacent box edge, alining mechanism adjacent which said box and cover edges are received and operable to engage and aline the projections for interengagement, means for shifting the box transversely of said edges and away from said alining mechanism after the alining operation, and means operable to deform and interlock said loops during said shifting movement of the box to fasten the cover closed.

18. A box lidding machine comprising a support onto which may be moved a box having an upwardly opened cover carrying a flexible projection at one edge interlockable with a second projection on an adjacent box edge, a movable crimping head overlying said edge of the box, means for moving the head downwardly to first move the cover to a nearly closed condition in which the projections are proximately positioned but not engaged and then further downwardly to close the cover and crimp the projections into interlocked relation, alining mechanism operable to engage and aline said projections, and means for actuating said alining mechanism to engage and aline said projections while the cover is in said nearly closed condition.

19. A box lidding machine comprising a movable support onto which is movable along a given path a box having a cover carrying a flexible projection interlockable with a second projection on an adjacent edge of the box, means for shifting said support transversely of said box path to move the box toward and away from a projection interengaging position, movable members operable to interengage said projections, and mechanism operable to actuate the members to so interengage the projections when the box is in said position.

20. A box lidding machine including a support onto which may be moved a box having a cover carrying a flexible projection interlockable with a second projection on an adjacent edge of the box, a pair of movable members extending along a pair of opposite sides of said support and engageable with the opposite walls of a box supported thereon to resist their bulging, means for actuating one of said members to shift the box in a first horizontal direction and into a projection interengaging position, and means for actuating the other of said members to shift the box in the opposite direction and out of said position.

21. A box lidding machine comprising a support onto which may be moved along a given path a box having a cover carrying a flexible projection interlockable with a second projection

on an adjacent edge of the box, means for shifting a box in opposite directions transversely of said path into and out of a projection interengaging position, means for ejecting a box along said path and from said support after a projection interlocking operation, and means for actuating said ejecting means in timed relation to said box shifting means.

22. A box lidding machine comprising a support for a box having a hinged cover carrying a series of first flexible wire loop projections at one edge interlockable with a corresponding series of second flexible wire loop projections on an adjacent edge of the box, means for bringing the box and cover from open to closed condition, upper and lower series of projection alining means positioned at the side of said box edge and engageable respectively with said first and second projections as the cover closes toward the box to retain the projections in alinement as they are engaged, and means positioned directly above said projection alining means and operable to interlock the projections.

23. A box lidding machine comprising a support for a box having a hinged cover carrying a series of first flexible wire loop projections at one edge interlockable with a corresponding series of second flexible wire loop projections on an adjacent edge of the box, means for bringing the box and cover from open to closed condition, upper and lower series of projection alining means positioned at the side of said box edge and engageable respectively with said first and second projections as the cover closes toward the box to retain the projections in alinement as they are engaged, means positioned directly above said projection alining means, and operable to interlock the projections and means mounting said alining means for movement relative to the box and said alining means.

24. A box lidding machine comprising a support onto which may be moved a box having an upwardly opened cover carrying at one edge a flexible loop projection interlockable with a second projection on an adjacent box edge, said projections being interengageable by the final closing movement of said cover, means for moving the cover downwardly toward its closed condition, a pair of spaced elements forming a guideway engageable with a side of the cover carried loop as it is closed by said last mentioned means to position said cover loop for proper interengagement with the box loop, means directly below said guideway operable to deflect the box loop longitudinally of the box edge, and crimping means operable to bend down and interlock the loops at the side of the box.
